HERBERT F. PRESCOTT, OF DETROIT, MICHIGAN.

DEVICE FOR STORING AND ADMINISTERING SERUMS.

SPECIFICATION forming part of Letters Patent No. 680,332, dated November 12, 1901.

Application filed September 6, 1900. Serial No. 29,126. (No model.)

To all whom it may concern:

Be it known that I, HERBERT F. PRESCOTT, a citizen of the United States, residing at Detroit, in the county of Wayne and State of Michigan, have invented certain new and useful Improvements in Devices for Storing and Administering Serums; and I do hereby declare the following to be a full, clear, and exact description of the invention, such as will enable others skilled in the art to which it appertains to make and use the same.

My invention relates to improved means for storing and administering serums; and its object is to provide means whereby the serum will be retained out of contact with the air during all the time of storage, shipping, dispensing, and administering the same and to provide the device by which this result is accomplished with certain new and useful features hereinafter more fully described, and particularly pointed out in the claims.

I have found that a closure in the nature of a piston fitted loosely enough to be moved in a cylinder and discharge its contents does not effectually exclude the air. Expelling the serum by means of air is objectionable, as the air thus comes in contact with the serum. I avoid these difficulties by providing the piston with a stem extending through a supplementary closure expressly adapted to exclude all air. I can thus fit the piston loosely enough to operate freely to discharge the serum and at the same time fully exclude the air from the serum at all times, as will more fully appear by reference to the accompanying drawings, in which—

Figure 1 is a side elevation of my improved storage, shipping, and dispensing vessel as it appears when filled with serum; Fig. 2, a vertical section of the same as it appears when prepared ready for administering the serum, and Fig. 3 a detail of the hypodermic needle and coupling for attaching the same to the storage vessel.

Like letters refer to like parts in all of the figures.

A represents the vessel to contain the serum, which vessel consists of a cylindrical body, of glass or other suitable material, having at one end a reduced prolongation A' A'',

closed at the end and having a transverse crease or groove B to facilitate breakage of the same at this place.

D is a perforated closure, of cork or other suitable material, through the perforation in which passes the stem or handle E of the piston C, which piston is adapted to freely traverse the cylindrical body A and expel the contents thereof, as hereinafter described.

F is a cap, of sealing-wax, paraffin, or other suitable material, surrounding the stem E and effectually sealing the passage in the closure D, through which the stem passes.

G is a hypodermic needle, having attached a tubular rubber coupling H, adapted to engage the extension A', as shown in Fig. 2.

From the foregoing the operation of my device will be readily understood.

The cylinder A is made of suitable size to contain a dose of the liquid serum, which being placed therein the piston C and supplementary closure D are then inserted and the sealing-wax F applied. The supplementary closure can thus be made sufficiently tight and impervious to air to effectually prevent any access of the same to the serum. In this condition the vessel containing the serum may be stored, transported, or dispensed, and when occasion arises to administer the serum the part A'' is broken off and the coupling H attached to the part A', as in Fig. 2, and the wax F detached from the stem E by rotating the stem or by removing the wax. By pressing the stem E inward the piston C will be moved in the body A and expel the contents thereof through the needle G.

After the contents of the device have been used the device will still be useful as a small syringe.

Having thus fully described my invention, what I claim, and desire to secure by Letters Patent, is—

1. The combination of a cylinder having a reduced and closed extension adapted to be broken transversely, a piston in the cylinder, and having a stem extending outside the cylinder, and a supplementary closure, surrounding the stem, and impervious to air substantially as described.

2. The combination of a cylinder having a

reduced and closed extension adapted to be broken transversely, a piston in the cylinder, a stem extending from the piston and outside the cylinder, a perforated closure in the end of the cylinder and surrounding the stem, and means for temporarily sealing the perforation in the closure substantially as described.

In testimony whereof I affix my signature in presence of two witnesses.

HERBERT F. PRESCOTT.
